(57) **CLAIM**

The ornamental design for a surgical site marking apparatus, as shown and described.

DESCRIPTION

FIG. 1 is a top perspective view of a surgical site marking apparatus showing my new design;

FIG. 2 is a top plan view thereof;

FIG. 3 is a cross-sectional view thereof taken along line 3—3 shown with FIG. 2;

FIG. 4 is a bottom plan view thereof;

FIG. 5 is an elevation of the top edge thereof, the side opposite being identical; and,

FIG. 6 is a left side elevation thereof, the side opposite being identical.
